UNITED STATES PATENT OFFICE.

FREDERICK SCHENKENBERG, OF DALLAS, TEXAS.

HORSE-COLLAR.

1,143,728.

Specification of Letters Patent. Patented June 22, 1915.

Application filed March 16, 1914. Serial No. 824,850.

To all whom it may concern:

Be it known that I, FREDERICK SCHENKENBERG, a citizen of the United States, residing at Dallas, in the county of Dallas and State 5 of Texas, have invented certain new and useful Improvements in Horse-Collars, of which the following is a specification.

My invention relates to new and useful improvements in horse collars. Its object is 10 primarily to prevent what is commonly known to saddlery workers as "grinning", this term being employed to denote a slight enlarging of the apertures or slits provided in the outer edge of the lining of a horse 15 collar to receive the thong lacing commonly employed to connect said edge to the corresponding edge of the front of the collar.

The object of the invention more specifically stated is to provide a horse collar having a welt superimposed upon the outer edge of the lining of the collar, which welt is held securely against the lining by the thong lacing which establishes connection between the outer edge of the lining and front of the 25 collar, this construction serving primarily to prevent "grinning", and serving also to protect the outer edge of the lining from wear and serving further to strongly reinforce the joint with which it is correlated, and increasing the useful life of the collar.

With the above and various other objects in view, my invention has relation to certain novel features of the construction and use, an example of which is described in the following specification, and is illustrated in the 35 accompanying drawing, wherein:

Figure 1 is a view showing the rear or lining side of a horse collar improved in accordance with my invention. Fig. 2 is a 40 transverse sectional view of the same, the section being taken upon the line x-x of Fig. 1.

Referring now more particularly to the drawing, wherein like reference characters 45 designate similar parts in both the figures, the numerals 1 and 2 respectively denote the front and lining of a horse collar, said members being curved in the usual well known manner to form between them a receptacle 50 for packing. The outer edge portions of the

members 1 and 2 are contiguous as indicated at 3, and are securely held in this relation by a thong lacing 4. The lacing 4 serves further to hold a welt or binder 5 firmly contiguous with said edge portion of the member 2, said welt having its outer edge flush with the corresponding edges of the members 1 and 2, and being bent at substantially a right angle adjacent to its inner edge, the edge portion thus bent being contiguous with the member 2 as indicated at 5^a. The welt or binder 5 absolutely prevents the thong-receiving slit at the edge of the lining from "grinning" or spreading. The defect of "grinning" in the horse collars 65 hitherto constructed is very objectionable since unless a very coarse packing material is employed, this material will gradually escape through the enlarged slits of the lining and eventually cause the collar to lose its 70 proper form and its utility as a pad. The welt or binding 5 furthermore constitutes a reinforcement to the joint between the outer edges of the members 1 and 2, and it also serves to protect the outer edge of the latter 75 member against wear.

The invention is presented as including all such changes and modifications as properly come within the scope of the device as claimed.

What I claim is:

In a horse collar the combination with the overlapping and outwardly extending edge portions of the front and lining of the collar of a welt provided with a right-angled 85 inner-edge, said welt disposed adjacent to said outwardly extending edge portions, a thong lacing passing through said edge portions and welt, and a seam adjacent to said lacing, passing through said welt and edge 90 portions, all arranged so that the right-angled inner-edge rests for support upon the lining of the collar.

In testimony whereof I have signed my name to this specification in the presence of 95 two subscribing witnesses.

FREDERICK SCHENKENBERG.
